UNITED STATES PATENT OFFICE

FRANK A. GAUGER AND ROY W. JOHNSON, OF MILWAUKEE, WISCONSIN, ASSIGNEES,
BY MESNE ASSIGNMENTS, TO TIME-O-STAT CONTROLS COMPANY, OF MILWAUKEE,
WISCONSIN, A CORPORATION OF MARYLAND

HEATER APPLIANCE

Application filed August 17, 1921, Serial No. 493,161. Renewed November 29, 1926.

This invention relates to certain new and useful improvements in heater appliances and, while the same refers more particularly to that type of heater generally employed for 5 supplying hot water to a household, it may be applied to any type of heater utilizing a fuel burner.

The present type of automatic household heating device is subject to many objections 10 among which are its expensiveness of operation and construction, and the dangers incidental thereto, in that should the pilot light become extinguished, a manipulation of the fuel control valve will permit the escape of 15 fuel and as a result be a serious danger to the life and property of the household.

Hence this invention has for one of its objects to provide a device of the class described in which the burner proper will be absolutely 20 disconnected from its course of fuel supply as long as the burner pilot light is extinguished.

It is another object of this invention to provide a pilot light arrangement which, upon the connection of the burner with its 25 source of fuel supply, flashes a jet of flame toward the burner.

Another object of this invention is to provide an improved valve construction disposed in the burner fuel supply line and so 30 designed and constructed that upon flashing the pilot, the burner will be connected with the fuel supply or, in the event the pilot should be extinguished, a flashing of the pilot will not connect the burner with its fuel 35 supply.

A further object of this invention is to provide a device of the class described so designed and constructed as to be capable of application to heaters now in use upon drilling of but one hole in the casing wall thereof adjacent the burner, whereby cost of installation is reduced to a minimum and the services of a skilled mechanic eliminated.

A still further object of this invention is to provide a pilot unit including thermostatic means which maintain the pilot supply open as long as the pilot is lit and which closes the pilot supply upon the pilot being extinguished whereby a diaphragm valve connected with the burner is restrained from

opening movement as long as the pilot is extinguished.

And a still further object of this invention resides in the provision of a single pipe arrangement for controlling the supply of fuel 55 to a burner, whereby the fuel supply will be positively disconnected from the burner upon extinction of the pilot.

With the above and other objects in view which will appear as the description proceeds, our invention resides in the novel construction, combination and arrangement of parts substantially as hereinafter described and more particularly defined by the appended claims, it being understood that such 60 changes in the precise embodiment of the herein disclosed invention may be made as come within the scope of the claims.

In the accompanying drawings, we have 70 illustrated one complete example of the physical embodiment of our invention constructed according to the best mode we have so far devised for the practical application of the principles thereof, and in which:

Figure 1 is an elevational view of a water 75 heating system equipped with our improved device;

Figure 2 is a view part in section and part 80 in elevation taken longitudinally through the fluid actuated device and the fuel supply controlling valve adapted to be actuated thereby;

Figure 3 is a view part in section and part 85 in elevation taken through the fuel control valve mechanism on the plane of line 3-3 of Figure 2;

Figure 4 is a view part in section and part 90 in elevation illustrating the construction of the improved pilot member and the thermostatic means operated thereby;

Figure 5 is a sectional view taken transversely through the pilot unit on the line 5-5 of Figure 4.

Figure 6 is a view similar to Figure 1 illustrating the burner control as independent 95 of the water supply;

Figure 7 is an enlarged view, part in section and part in elevation illustrating the manner of connecting the control illustrated in Figure 6 with the fuel supply valve, and 100

Figure 8 is an enlarged detailed sectional view taken on the line 8—8 of Figure 7.

Referring now more particularly to the drawings, 6 designates a water tank of any well known construction and having a water supply pipe 7 connected therewith and an outlet pipe 8 leading therefrom, near the top thereof, to a faucet 9. The water in tank 6 is heated by a device which may be of the usual construction comprising an outer casing 10, a water coil 11 having its lower end connected with the lower portion of tank 6 by a pipe 12 and its upper end connected with the top of the tank by a pipe 13, and a burner 14 so arranged that its flames play on the coil.

The burner 14 is connected with a source of fuel supply by a pipe line 15 provided with an improved form of control valve construction adapted to be operated by the means depicted in Figures 1 and 2 or by the means illustrated in Figures 6 to 7.

The valve construction is in the form of a two part casing 16 divided into an upper chamber 17 and a lower chamber 18 by a diaphragm 19 carrying a nipple or valve member 20 arranged to normally seat within a counter-bored boss 21 providing a central outlet for the lower chamber 18. One end 30 of the section of pipe 15 in direct connection with the burner 14 is connected with the chamber 18 outlet.

The pressure end of the supply pipe 15 is connected with the lower chamber 18, as best shown in Figure 3, so that the full volume and pressure of the gas at all times flows therethrough. The chamber 17 is of greater area and volume than chamber 18 and said chambers are connected by an adjustable bypass 22, 40 see Figure 3, whereby, by reason of the variance of the volume in the chambers, the diaphragm 19 will be normally urged toward chamber 18 to seat member 20 in the outlet and disconnect the fuel supply from the burner.

The upper part of the valve casing is provided with a bored enlargement 23 in which is positioned an auxiliary control valve 24 for the flow of fuel from chamber 17 to a pilot light tip 25, to be later described. The valve 24 is in the form of an outer sleeve 26 having its inner end 27 normally slightly spaced from a seat 28 formed within the bore of enlargement 23 whereby there is at all times a slight leakage of the fuel therewith which is conducted to the pilot tip 25 through a port 29 and pipe 30 in order that a small flame may be constantly maintained at the pilot tip. To insure the maintaining, by the diaphragm 19, 60 of the valve member 20 in closing position, the normal volume of fuel supplied to the pilot is less than that supplied chamber 17 through bypass 22.

That portion of sleeve 26 adjacent port 29 65 is annularly channeled and provided with a

plurality of ports 31 in communication with the sleeve central bore. A valve member 32, normally held in closing position by a spring 33, has its stem slidably mounted in the sleeve bore and the outer end thereof has a push button 34 thereon adapted to be engaged by the stem 35 of a fluid actuated plunger 36, to be later described. The valve member 24 may be of any special design and, in the present instance, the one illustrated is similar to that depicted in U. S. Patent No. 1,417,510, granted to us May 30, 1922.

The pilot light unit consists of a casting 37 counterbored to receive a hood or protecting cylinder 38, which is readily removably secured therein by frictional engagement, and said casting has a securing stem 39, the outer end of which is reduced and threaded, as at 40, for insertion through an aperture 41 made in the wall of casing 10, 85 a lock nut 42 making the casting fast. The stem 39 is provided with a bore 43 which is preferably disposed on a plane slightly above burner 14, see Figure 4. The pipe 30 is connected with a centrally apertured lug or boss 44, in communication with the interior of cylinder 38 to one side of the center thereof and the flow of fuel through the pipe is controlled by a rod 45 having its lower end tapered, as at 46, to provide a valve member 90 and its upper end threaded, as at 47, for readily adjustable connection with a cap 48 mounted on the upper end of a tube 49, the lower end of which is secured in casting 37, 100 said tube and rod forming a thermostatic device as will be later described. Communicating with the interior of the tube 49, outwardly of the rod end 46, is a bypass 50 in connection with the pilot tip 25, which is also enclosed by the cylinder 38, said pilot tip 10 having a jet or flash opening 51 in register with the stem bore 43.

The pilot tip 25 is also provided with a top jet 52 of a less area than jet 51, whereby a small flame, as illustrated by dotted lines 11 in Figure 4, will at all times subject the tube 49 to its heat and, consequently expand the same to free the rod end 46 from the opening of lug 44. The pilot light is guarded by a frusto-conical sleeve or cylinder 53 provided in its side walls with a plurality of jet apertures 54 one of which registers with the jet 51 and bore 43. The rod 45 is preferably solid and formed of Bessemer steel, or iron, or any other material having a relatively small degree of expansibility under heat, and tube 49 is preferably constructed of brass or any other material having a greater degree of expansibility under heat influence, whereby upon the tube 49 being subjected to the heat of the pilot flame, the same will expand and lift rod 45 free of port 44, however rod end 46 is preferably so adjusted as to be slightly off seat when tube 49 is fully contracted.

The pipe line 8 leading from tank 6 to the faucet 9 is medially disconnected and has one end 55 thereof connected with the inlet 56 of a casing 57 and the end 58 thereof connected with the casing outlet 59. A partition 60 separates the inlet and outlet and has a central bore 60' therein preferably in substantial axial alignment with the stem of valve 24 and through which port plunger 35 passes, the plunger or valve member 36 being slidably mounted in that portion of casing 57 with which end 55 of line 8 is connected.

The rod or stem 35 passes outwardly through an opening in wall 57' of the casing nearest the valve 16 and has its extreme outer end positioned adjacent cap 34, a stuffing box or gland 61 surrounding the stem to prevent the leakage of the fluid therewith. With this construction, it will be obvious that a movement of the plunger 36 from left to right, with reference to Figure 2, will cause stem 35 to engage cap 34 and move valve 32 inwardly to permit an excess flow of fuel to the pilot, as will be hereinafter described, such movement of the plunger being yieldably resisted by a spring 62 coiled about stem 35 and confined between wall 57' and the valve head portion or boss 63 of the plunger.

The inlet 56 has a partition 64 dividing the same from that portion of the casing in which the plunger is mounted and said partition has a large and a small port 65 and 66, respectively, the port 65 communicating with the side of the plunger nearest partition 60 and the port 66 communicating with the other side thereof when the plunger is in its position freeing the port 60' to permit flow of fluid through the casing from pipe section 55 to section 58. The port 65 is of such an area that, when the faucet 9 is fully open, the flow of fluid through pipe section 55 will be of such volume as to more than fill said port area as a result of which the pressure acting on the rear of plunger 36, by reason of the port 66 communicating therewith, will become greater than the force of spring 62 and move the plunger to the right with reference to Figure 2.

As the plunger moves to the right, the area of port 65 decreases and the pressure thus exerted on the outer face of the plunger is materially increased to apply the extra force necessary to overcome the increased tension of spring 62 as the same is compressed. The plunger 36 moves against the action of spring 62 until it almost completely closes port 65 and prevents any substantial flow of fluid from one part of pipe 8 to the other and at the same time opens valve 24 in the manner hereinbefore described to light burner 14.

As long as faucet 9 is fully open, plunger 36 holds valve 24 open and when the operator is of the opinion that the water within tank

6 is sufficiently hot, the faucet is closed. Upon closing the faucet, springs 62 forces plunger 36 to its normal position and the fluid between the plunger and casing end wall 67 passes through a minute equalizing hole 68 in the plunger and the valve 24 is closed by its spring 33. The operator may then open the faucet to any point up to that where the volume of water passing through pipe 8 is not greater than the area of port 65 to obtain the heated water within the tank.

The operation of the device is adjustable as wall 67 is in the form of a threaded plug secured in the outer end wall of the casing 57 and carries a threaded stem 68' having its inner end abutting plunger 36 when in its normal position, said stem being provided with a knurled head for convenience in obtaining instant adjustment.

A stuffing box or gland 70 surrounds stem 68' at its point of passage through the end cap to prevent leakage therewith. The valve member 16 and casing 57 are readily detachably secured together in proper alignment by a bracket member 71' one end of which is secured to the valve casing and the other end to the casing 57.

From the foregoing description taken in connection with the accompanying drawings, it will be readily appreciated that when plunger 36 is actuated by manipulation of faucet 9, as heretofore described, to compress valve spring 33, a full flow of fuel is permitted from valve chamber 17 to the pilot light, which is materially greater in volume than that flowing through bypass 22 and consequently the pressure within chamber 17 is decreased to a degree less than that in chamber 18 and the diaphragm raised upwardly to register ports 20' of valve 20 with chamber 18 and permit the fuel to flow to the burner. However, should the pilot light be out, tube 49 will have become chilled and contracted to bring the rod end 46 to almost seating position so that the opening of valve 24 will not permit the flow of fuel from chamber 17 through pipe 30 at a rate greater than that through bypass 22, whereby actuation of plunger 36 will not connect burner 14 with the fuel supply through chamber 18.

In order to insure the necessary supply of oxygen for the burning of the pilot, casting 37 is provided with a plurality of bottom openings 37', see Figure 5, and the top end of tube 38 is apertured as at 38'. By reason of the pilot plug jet opening 51 being of greater area than opening 52, a manipulation of valve 24 will flash a jet of flame from opening 51 toward the burner, as illustrated in Figure 4, the flame at opening 52 being only slightly increased, as will be readily apparent. When valve 24 is closed the gas escaping from jet 51 burns in a common flame with that escaping from jet 52 to maintain

tube 49 at a temperature sufficient to insure proper opening of the port 44.

In Figures 6 to 8 we have illustrated the use of our invention independent of the water supply actuated means where a control member is positioned at some convenient place for actuation to light the burner. In this form of our invention the valve 24 is eliminated and an outlet 71 leads from the valve chamber 17 and is connected with an auxiliary control valve 72 by a pipe 73. The valve 72 consists of a casing 74 having an inlet 75 and an outlet 76, a rotatable valve member 77 being operable to connect and disconnect said inlet and outlet. A handle 78 is carried by the valve member and provided with a pointer adapted to register with the designation "off" when the inlet and outlet 75 and 76 are disconnected and with the designation "on" when the inlet and outlet are in connection.

A pipe 79 leads from the outlet 76 to one end of a passage way 80 formed in a boss 81 on the valve casing 16 and to the other end of which is connected the pipe 30 hereinbefore described. The normally constant supply of fuel to the pilot light is obtained by a bypass 82 which leads from the port 71 to the passage way 80, the volume of fuel 30 passing through the bypass being controlled by an adjustable needle valve 83.

This form of our invention is substantially the same as that illustrated in Figures 1 to 4, in that the volume of the fuel passing from the chamber 17 to the pilot through pipe 30, passage 80, bypass 82 and outlet 71, is less than that entering chamber 17 through bypass 22. However, upon turning handle 78 to register with designation "on" pipes 73 and 79 are connected and the fuel within chamber 17 flows through outlet 71, pipes 73 and 79, passage 80 and pipe 30 to the pilot in a volume greater than that entering chamber 17 through bypass 22, as a result of which the pressure on the under side of the diaphragm 19 becomes greater than that on the upper side and the valve member 20 raises to permit the egress of the fuel outwardly to the burner 14.

From the foregoing description taken in connection with the accompanying drawings it will be readily apparent to those skilled in the art to which an invention of this character appertains that we have provided what may be properly termed a single pipe controlling means for a pilot light which prevents the connecting of the burner when its supply upon the pilot light is extinguished and thus eliminates all dangers incidental to the expense of fuel were the burner to be connected with its supply without being lit.

What is claimed is:

1. In a device of the class described, a fuel supply, a burner connected with said supply, a valve for controlling the flow of fuel to the

burner, a pilot light, means for flashing said light and means operating substantially following the flashing of the pilot light to operate said valve to supply fuel to the burner.

2. In a device of the class described, a fuel supply, a burner connected with said supply, a valve for controlling the flow of fuel to the burner, a pilot light, a pilot light valve normally maintaining a minimum volume of fuel to the pilot light and adapted upon actuation to supply an increased volume of fuel thereto and flash the pilot light, and fluid actuated means for simultaneously actuating the pilot light valve to flash said light and operating said first-named valve to supply fuel to the burner. 70 75 80

3. In a device of the character described, a fuel supply, a burner connectible with said supply, a valve controlling the flow of fuel to the burner, a pilot light, means supplying a minimum volume of fuel to the pilot light, a normally closed valve adapted, upon opening movement, to supply an increased volume of fuel to the pilot, and means operable by the increased volume of fuel passing through said second mentioned valve upon the opening thereof to open the first-mentioned valve and connect the burner with the fuel supply. 85 90

4. In a device of the character described, a fuel supply, a burner connectible with said supply, a valve controlling the flow of fuel to the burner, a pilot light, means supplying a minimum volume of fuel to the pilot light, a normally closed valve adapted, upon opening movement, to supply an increased volume of fuel to the pilot, means operable upon opening of said second mentioned valve to open the first mentioned valve and connect the burner with the fuel supply, and means preventing opening movement of the first-named valve while the pilot light is extinguished. 95 100 105

5. In a device of the class described, a control valve positioned within a fuel supply for controlling the flow of fuel to a burner, said valve comprising a casing, a diaphragm dividing said casing into two chambers into one of which said fuel supply discharges, an outlet leading from said last mentioned casing chamber, a valve member carried by said diaphragm for controlling said outlet, a bypass connecting said casing chambers whereby the pressure on the side of the diaphragm remote from the chamber into which the fuel supply discharges will be greater than that on the other side thereof to normally maintain said outlet closed, a pilot light for the burner, means connecting said pilot light with the chamber on the side of the diaphragm remote from the chamber into which the fuel supply discharges whereby a normal supply of fuel of less volume than that passing through said bypass is furnished the pilot light, and means for increas- 110 115 120 125 129

- ing the supply of fuel to the pilot light to a volume greater than that passing through said bypass whereby the pressure on the side of the diaphragm with which the pilot light 5 supply is connected is decreased to an amount less than that on the other side of the diaphragm to permit opening of the fuel outlet.
6. In a device of the class described, a 10 control valve positioned within a fuel supply for controlling the flow of fuel to a burner, said valve comprising a casing, a diaphragm dividing said casing into two chambers into one of which said fuel supply dis- 15 charges, an outlet leading from said last mentioned casing chamber, a valve member carried by said diaphragm for controlling said outlet, a bypass connecting said casing chambers whereby the pressure on the side 20 of the diaphragm remote from the chamber into which the fuel supply discharges will be greater than that on the other side thereof to normally maintain said outlet closed, a pilot light for the burner, means connecting said pilot light with the chamber into which the fuel supply discharges whereby a normal supply of fuel of less volume than that passing through said bypass is furnished the pilot light, and means for increasing the supply of fuel to the pilot light to a volume greater than that passing through said bypass whereby an increased amount of fuel is supplied to the pilot light to flash said light to play on said burner and the pressure on 30 the side of the diaphragm with which the pilot light supply is connected is decreased to an amount less than that on the other side of the diaphragm to permit opening of the fuel outlet.
- 35 7. In a device of the class described for use with a burner, a pilot light, means for constantly supplying a normal amount of fuel to the pilot light, means for supplying a greater amount of fuel to the pilot light to 40 flash the same toward the burner, a thermostatic member controlling the supply of fuel to the pilot light and adapted upon extinction of the pilot light to substantially shut the said supply means, a common guard housing 45 for said pilot light and thermostatic member, and a sleeve mounted within said housing and surrounding the pilot light to shield the same.
- 50 8. In a device of the class described, a pilot light, means for constantly supplying a normal amount of fuel to the pilot light, means for supplying a greater amount of fuel to the pilot light to flash the same toward a burner, 55 said pilot light having a jet opening in its tip and a jet opening in the side thereof, and a frusto-conical member surrounding said pilot with its reduced open end aligning with the jet opening in the tip of the pilot and the 60 opening in the side thereof communicating with the jet opening in the side of said pilot from which said pilot flashes.
9. In a device of the class described, a pilot tip having a jet opening in its top and a jet opening in the side thereof with its axis at right angles to the axis of the top jet opening, said side jet opening being of greater area than said top jet opening, means for supplying a normal amount of fuel to said pilot tip whereby a constantly burning pilot flame will be maintained, the fuel escaping from said side jet opening passing upwardly to burn in a common flame with the fuel escaping from said top jet opening, and means for supplying a greater amount of fuel to the pilot tip whereby a jet of flame will be flashed from said side jet opening by reason of the same being of greater area than said top jet opening.
10. In a device of the class described, a pilot tip having a jet opening in its top and a jet opening in the side thereof, said side jet opening being of greater area than said top jet opening, means for supplying a normal amount of fuel to said pilot tip whereby a constantly burning pilot flame will be maintained, the fuel escaping from said jet opening passing upwardly to burn in a common flame with the fuel escaping from said top jet opening, means for supplying a greater amount of fuel to the pilot tip whereby a jet of flame will be flashed from said side jet opening by reason of the same being of greater area than said top jet opening, and thermostatic means positioned within the influence of the constant burning pilot flame which means substantially close said pilot fuel supply upon said pilot flame becoming extinguished.
11. In a device of the character described, a casting including a base and a tubular stem part, a fuel supply passage leading into the base and having its end therein counterbored to provide a valve seat, a tube having a comparatively high coefficient of expansion, the lower end of said tube being secured to the base with its bore in register with the counterbored part of said fuel supply, a rod carried by said tube and positioned therein, said rod having a relatively low coefficient of expansion and the lower end thereof engaging said valve seat when said tube is contracted to close the fuel supply, a pilot tip mounted on the base, and a bypass connecting the pilot tip with the fuel supply at a point above the valve seat, the pilot, when lit heating the tube to expand the same, the end of said rod being held free of the valve seat when the tube is expanded, said tube contracting upon extinction of the pilot light to engage the rod end with the valve seat to disconnect the pilot from the fuel supply.
12. In a device of the character described, a casting including a substantially cup-shaped part and a tubular stem part, the bore of

which communicates with the interior of the cup-shaped part, a fuel supply passage leading into said cup portion and having its end therein counterbored to provide a valve seat, a tube member having a comparatively high coefficient of expansion, the lower end of said tube being secured to the casting with its bore in register with the counterbored part of said fuel supply, a rod carried by said tube and positioned therein, said rod having a relatively low coefficient of expansion and the lower end thereof engaging said valve seat when the tube is contracted to close the fuel supply, a pilot tip mounted in said cup-shaped portion, a bypass connecting the pilot tip with the fuel supply at a point above said valve seat, the pilot, when lit heating the tube to expand the same, the end of said rod being held free of the valve seat when the tube is expanded, said tube contracting upon extinction of the pilot light to engage the rod end with the valve seat to disconnect the pilot from the fuel supply, and a guard carried by the cup-shaped portion of the casting and enclosing said tube and pilot.

13. In a device of the character described, a casting including a base and a tubular stem part, a fuel supply passage leading into the base and having its end therein counterbored to provide a valve seat, a tube member having a comparatively high coefficient of expansion, the lower end of said tube being secured to the casting with its bore in register with the counterbored part of the fuel supply, a rod carried by said tube and positioned therein, said rod having a relatively low coefficient of expansion and the lower end thereof engaging said valve seat when the tube is contracted to close the fuel supply, a pilot tip mounted on the base, and a bypass connecting the pilot tip with the fuel supply at a point above said valve seat, the pilot, when lit, heating the tube to expand the same, the end of said rod being held free of the valve seat when the tube is expanded, said tube contracting upon extinction of the pilot light to engage the rod end with the valve seat to disconnect the pilot from the fuel supply, said pilot tip having a jet opening in its side registering with the bore of the tubular stem and a jet opening in its top whereby a jet of flame is played on the thermostat and through the tubular stem to play on a burner to be ignited and a frusto-conical shield within said guard having an aperture in its side wall thereof in register with the jet opening in the side of the pilot tip and an opening in its side to permit the pilot to burn through the jet opening in the top thereof.

14. In a heating system of the class described, the combination of a water receptacle having an outlet valve and fuel burners adapted to heat the contents of said receptacle, a source of fuel supply for said burners, a valve controlling the supply of fuel to the burners, a pilot light, means for supplying a minimum volume of fuel to the light, said outlet valve adapted upon opening movement to control the supply of an increased volume of fuel to the light, and means operable upon the opening of the first-mentioned valve to open the second-mentioned valve and connect the burner with the fuel supply.

15. In a heating system of the class described, the combination of a water receptacle having an outlet valve and fuel burners adapted to heat the contents of said receptacle, a source of fuel supply for said burners, a valve controlling the supply of fuel to the burners, a pilot light, means for supplying a minimum volume of fuel to the light, means operable upon the opening movement of the outlet valve to increase the volume of fuel to the pilot light, and a second means operable upon the opening of the first mentioned valve to open the second-mentioned valve and connect the burners with the fuel supply.

16. In a system of the character described, a main burner, a main supply line therefor, a main valve in the supply line, a pilot burner, a control valve, thermostatic means associated with the pilot burner for operating said control valve and means operable in accordance with the opening and closing

carried by said tube and positioned therein, said rod having a relatively low coefficient of expansion and the lower end thereof engaging said valve seat when the tube is contracted to close the fuel supply, a pilot tip mounted in said cup-shaped portion, a bypass connecting the pilot tip with the fuel supply at a point above said valve seat, the pilot, when lit heating the tube to expand the same, the end of said rod being held free of the valve seat when the tube is expanded, said tube contracting upon extinction of the pilot light to engage the rod end with the valve seat to disconnect the pilot from the fuel supply, a guard carried by the cup-shaped portion of the casting and enclosing said tube and pilot, said pilot tip having a jet opening in its side registering with the bore of the tubular stem and a jet opening in its top whereby a jet of flame is played on the thermostat and through the tubular stem to play on a burner to be ignited and a frusto-conical shield within said guard having an aperture in its side wall thereof in register with the jet opening in the side of the pilot tip and an opening in its side to permit the pilot to burn through the jet opening in the top thereof.

17. In a heating system of the class described, the combination of a water receptacle having an outlet valve and fuel burners adapted to heat the contents of said receptacle, a source of fuel supply for said burners, a valve controlling the supply of fuel to the burners, a pilot light, means for supplying a minimum volume of fuel to the light, said outlet valve adapted upon opening movement to control the supply of an increased volume of fuel to the light, and means operable upon the opening of the first-mentioned valve to open the second-mentioned valve and connect the burner with the fuel supply.

18. In a system of the character described, a main burner, a main supply line therefor, a main valve in the supply line, a pilot burner, a control valve, thermostatic means associated with the pilot burner for operating said control valve and means operable in accordance with the opening and closing

of said control valve for opening and closing the main valve.

18. In a system of the character described, a main burner, a supply line therefor, a main valve in said supply line, a control valve remote from said main valve, a fluid pressure motor for controlling the position of said main valve and connections between said remote control valve and said fluid pressure motor for causing a variation in pressure in the motor and thereby actuating the same upon the opening and closing of said remote control valve.

19. In a system of the class described, a main burner, a supply line therefor, a main valve in said supply line, a control valve, means operable in response to variations in gas pressure for operating said main valve and connecting means between said pressure operated means and said control valve for causing variations in pressure in said pressure operated means in accordance with movement of said control valve.

20. In a system of the class described, a main burner, a main valve controlling the supply of fuel to the burner, a pilot burner for igniting the main burner, a pilot valve independent of said main valve for controlling the supply of fuel to the pilot burner, a thermostat for operating said pilot valve, said thermostat being associated with said pilot burner to be influenced by heat produced thereby and so isolated as to be substantially unaffected by heat produced by combustion at the main burner and means for operating said main valve upon the operation of said pilot valve.

40 In testimony that we claim the foregoing we have hereunto set our hands at Milwaukee, in the county of Milwaukee and State of Wisconsin.

FRANK A. GAUGER.
ROY W. JOHNSON.
